UNITED STATES PATENT OFFICE.

WELLINGTON P. KIDDER, OF MALDEN, ASSIGNOR TO THE KIDDER PRESS
MANUFACTURING COMPANY, OF BOSTON, MASSACHUSETTS.

PRINTING-MACHINE.

SPECIFICATION forming part of Letters Patent No. 291,521, dated January 8, 1884.

Application filed October 30, 1882. (No model.)

To all whom it may concern:-

Be it known that I, WELLINGTON PARKER KIDDER, of Malden, in the county of Middlesex and State of Massachusetts, have invented 5 certain Improvements in Printing-Machines, of which the following is a specification, reference being had to the accompanying drawings, showing a printing-machine which is the best form of apparatus now known to me 10 for putting my invention into practice, and which also embodies certain features of my invention.

The essential operations in printing are properly classified as, first, inking the form; 15 second, presenting the sheet or web to receive the impression from the inked form; third, taking the impression; and, fourth, delivering the printed sheet.

The paper H is fed from a roll, (not shown 20 in the drawings,) and is slackened off from this roll, as described in my Patent No. 224,440, dated February 10, 1880. It passes between clamps h h', attached to the frame of the machine, the moving member h' of which is actuated by the cam h², and thence over shaft h³, 25 partially around impression-cylinder D, thence partially around impression-cylinder D', and thence over shafts h⁴ and h⁶, and between the feed-rolls h⁵ and h⁸. The shaft h⁵ is mounted 30 upon the carriage F. On the impression or forward stroke of cylinder D the paper is first nipped between cylinder D and the form at the line marked 1 in the diagrams, Figures 1 and 2, and that part of the paper between 1 35 and 2 receives the impression from form B, so that at the end of the impression the paper near the line marked 2 is nipped between the form B and cylinder D. Now, all that part of the paper from 1 to 2 would remain flat upon 40 and sticking to form B at the end of the impression were it not for the shaft h³ and the clamps h h'; but as the paper is held by the clamps it renders over shaft h³, as that shaft rises, and is therefore stripped off the form 45 with the least possible resistance from the stick of the ink, and at the end of the impression-stroke the paper between the line held by clamps h h' and the line 2 is as shown in Fig. 2. The paper from 2 to 3 receives the impression 50 from form B'; and is stripped off from

form B' by the motion of cylinder D over form B.

Fig. 1 is a diagram showing clearly the position of the paper at the beginning of the stroke to make the impression when two forms 55 are used—that is, when my press is a perfecting-press; and Fig. 2 is a like diagram, but showing the position of the paper after the impression has been taken. It will be clear from these diagrams that the function of shaft 60 h³ is to prevent the paper from bagging between it and the line where the paper is nipped between cylinder D and form B, and that this function is performed for cylinder D' by the cylinder D. Cylinder D' also performs an im- 65 portant duty in aid of cylinder D—that is, it keeps the paper between 1 and 2 away from the form until the moment before it is nipped between the form and the impression-cylinder. This duty is performed for cylinder D' 70 by the shaft h⁵.

To prevent undue strain upon the paper lying between the line marked 2, where it is nipped by the cylinder D' and form B', and the line where it is nipped by the feed-rolls h⁷ h⁸, the 75 swinging shaft h⁵ is swung inward gradually, thereby slackening the paper as required to relieve it from strain; or shaft h⁵ may be mounted in the frame of the machine, and a shaft, h¹⁰, be mounted on carriage F, as shown in Fig. 80 5, the shaft h¹⁰ then performing the same office for the paper between 2 and 3 that cylinder D' performs for the paper between 1 and 2.

In the diagrams, Figs. 3 and 4 I have illustrated this the main feature of my invention, 85 where only one form is used, instead of two forms, as in my perfecting-press. In these diagrams the shaft h³ is a roll, which is pressed against the cylinder D during the impression, and consequently performs the functions 90 95 which in the other diagrams are performed by the clamps h h' and the shaft h³, for, as the surface speed of h³ is just equal to that of the cylinder D, the paper is clamped, and also guided substantially as before. The shaft h¹⁰ performs the same function in these diagrams, 100 Figs. 3 and 4, for cylinder D as cylinder D' does in the other diagrams for cylinder D, for cylinder D' may be regarded as omitted from these diagrams, or, what is the same thing,

the form B' may be regarded as omitted, and therefore cylinder D' ceases to be an impression-cylinder, and its only function is to keep the paper between 1 and 2 away from form B 5 until the moment cylinder D is ready to force it against form B.

I have thus fully described the mode of presenting the web, as it aids much in understanding my new machinery for printing, which is 10 shown in the drawings, and which I will now describe.

Figs. 1, 2, 3, and 4 are the diagrams herein-before referred to. Fig. 5 is a side elevation, showing the impression-cylinders in position 15 to begin the impression-stroke. Fig. 6 shows the opposite side and the impression-cylinders after the impression-stroke. Fig. 7 is a rear elevation, partly in section. Fig. 8 is a plan view, partly in section, showing the arrangement 20 of the cylinders and driving-gear. Fig. 9 is a detail illustrating the form-inking mechanism and the mechanism for operating the fountain.

The frame of the machine shown in the drawings consists of two upright pieces, A A', a base, 25 A², and the two beds, A³ A⁴, the beds connecting together the uprights A A', and the whole constituting a strong and simple frame. The beds A³ A⁴ support the type-forms B B'. The 30 impression-cylinders D D' are mounted in carriage F, which is fitted in ways in the uprights A A'. This carriage F is reciprocated by means of connecting-rods f and wrist-pins f', which are fast to the main wheels f². These wheels 35 f² are fast to the main shaft f³, and one of them is geared to pinion f⁴ on the driving-shaft f⁵. At each revolution of the main shaft f³ the carriage F moves up to the position shown in Fig. 6, and back to place, as shown in Fig. 5, 40 the journals d of the impression-cylinders D D' are mounted in eccentric boxes d', and these boxes d' are themselves mounted in boxes in the carriage F. Each eccentric box d' is fast to an arm, d², and these arms are 45 connected by rod d³, this mechanism causing the eccentric boxes d' to throw the cylinders D D' apart at one end of their stroke and to bring them together at the other end by means of cams d⁴ d⁵, as will be plain from the drawings. 50 Each of the cylinders D D' is caused to revolve during its impression-stroke at a speed which will cause it to roll over the form without slip by means of gear-wheel d⁶ and rack d⁷, and the teeth of this gear and its rack are 55 of such a length that they will remain in mesh when the cylinder is away from the form during its return-stroke.

The form-inking rollers G and the ink-distributing rollers g g' g² are also carried by the 60 carriage F, the form-inking rollers G rolling upon the form on both the forward and back stroke of the carriage. The rollers g g² are metal inking-rollers, and are driven by a train of gears connecting with racks g⁴. (See Fig. 65 9.) Each gear g³ meshes with a rack, g⁴, and also with a gear fast on the end of the roller g. This gear on roller g connects with a gear on

roller g² by an intermediate gear. The distributing-roller g' revolves with rollers g and g², and also has an endwise reciprocating movement, all as in the well-known "rack-and-screw" distribution. The duct-rolls g⁵ are mounted in levers g⁶, which are fulcrumed on carriage F. Each duct-roll is held against its metal ink-distributing roll g² by a suitable 75 spring, except when the carriage F is near the end of its return-stroke, and during this time the friction-roll on the lever g⁶ enters cam g⁷, and the duct-roll is thereby forced into contact with the roll of the fountain g⁸. These 80 fountains g⁸ are of the usual construction, except that their rolls are revolved by the pawl-and-ratchet mechanism g⁹, actuated by the levers g¹⁰ g¹¹ and the cam g¹². The ratchet is fast to one end of the fountain-roll g⁸, and the 85 pawl is fulcrumed on the lever g¹⁰.

The feed-rolls h' h⁸ and shears J are constructed and operated as described in my patent before referred to, No. 224,440, of February 10, 1880, and need no further description 90 here. The swinging shaft h⁵ is operated by connecting-rod h¹¹, which at its lower end is attached to lever h¹², actuated by a cam.

The operation is as follows: Assuming the paper to have just been fed the proper distance, which in the machine shown is the length of the form B, (or of the form B', for each is of the same length,) plus the margin, the clamp h h' is closed, (or the paper is held in any other suitable way,) and consequently a 95 portion of the web will be held at two points—namely, the clamps h h' or their equivalent, and the feed-rolls, the printing apparatus being all between these two points—and the slack having been taken out of the paper between 100 these two points, for the feed-rolls h' h⁸ have just pulled the paper through the machine and over a number of guiding-shafts, as well as over portions of the impression-cylinders, the impression-cylinders now commence their 105 impression-stroke, and the paper is nipped at 1 between form B and cylinder D, and at 2 between form B' and cylinder D'. As the cylinders continue their impression-stroke the paper is pulled off form B in rear of cylinder D 110 by shaft or roll h³, and off form B' in rear of cylinder D' by cylinder D, and is prevented from touching form B too soon by cylinder D, and from touching form B' too soon by shaft h⁵, (or h¹⁰, when that is used; but for certain 115 classes of work I prefer to use the swinging shaft h⁵ rather than to use h¹⁰, as when using heavy ink, which is liable to be blurred by passing over shaft h¹⁰.) At the end of the impression-stroke the cylinders are brought 120 closer together, so that they will not bear on the forms on their back-stroke, and at or just before the end of the impression-stroke the clamp is opened and the paper is pulled forward by the feed-rolls, the feed taking place 125 during the back-stroke of the impression-cylinders. Near the end of the back-stroke the duct-rolls g⁵ are brought into contact by means of the levers g⁶ and cams g⁷ with the rolls of the

fountains g^3 , and take up a supply of ink, and as the carriage F moves again on the impression-stroke the levers of these duct-rolls are drawn out of their cams, and the duct-rolls come into contact with the metal ink-distributing rolls g^2 and supply them with ink, which is distributed in a well-known manner. As the form-inking rolls G are mounted upon the carriage F, they are carried over the forms during the impression-stroke of the carriage F, and carried back again over the form during the return-stroke of the carriage.

When the paper passes directly from cylinder D to cylinder D', as shown in the drawings, and two forms are used, the register depends upon the length of feed and the position of the types in each chase. Consequently the paper, after leaving cylinder D, should be carried under a shaft, h^4 , which is adjustable, in order to obtain a correct register of any desired length of sheet, to avoid the need of any exact relative adjustment of the types in each form. The shaft h^4 is a guide-shaft, and used to prevent the paper coming into contact with the cover g^3 of the inking-rolls. (See Fig. 9.)

It will be obvious that the feed-rolls h^7 h^8 might be in the position occupied by h^6 (or by h^5 , if the web were passed around h^{10} and the swing of h^5 thereby rendered needless) were it not for the presence of the press K. This press K is for the purpose of printing matter with a different-colored ink from that used on forms B and B'. It is so timed that its impressions are taken during the impression-stroke of the carriage F, as the same feed, h^7 h^8 , serves for all three of the presses. This third press is designed, mainly, for printing advertisements in newspapers or the like in ink of a color so different from that used for the surrounding matter as to make them prominent.

Inasmuch as the impression from form B on that part of the paper between 1 and 2 is outermost at the next succeeding impression-stroke of cylinder D', it is desirable, in order to prevent smearing, to change the tympan-paper used with cylinder D, and for this purpose a reel, L, is mounted in cylinder D', the paper from which passes through a slit in the cover of cylinder D' and past suitable guides, h^{10} and l' , to a reel, l^2 , on frame A. From time to time the reel l^2 is turned, in order to unwind the tympan-paper l from reel L, and thus present a dry surface to bear upon the freshly printed side of paper H, and when the greater part of the tympan-paper l is unwound from reel L it is rewound upon that reel from time to time. This can be readily done by the operator by means of suitable handles, (not shown); or mechanism for moving either of the reels L or l^2 at regular intervals may be readily devised and applied to the press.

The main wheels f^2 have counter-weights f^6 applied to them to balance the weight of the carriage F and the other parts, so that the machine may run smoothly at the rate of, say, sixty revolutions per minute. At each revo-

lution of the press shown in the drawings a newspaper printed on both sides, with one or more advertisements in red or some other striking color, is deposited on the table of the machine at M.

The forms B B' are put in and taken out at that side of the machine which is shown in Fig. 5, the racks being at the other side. One of the bearers on each bed is preferably rigidly attached to or in one piece with the chase of that bed, as it must be taken out to receive the chase.

It is often desirable to run the machine without taking the impression, and for this reason cams d^4 are mounted, as shown, so that by a motion of lever d^8 the cylinders are not separated at the end of their return-stroke.

I am aware of Patent No. 83,471, of 1868, granted to Royal Cummings, and disclaim all that is therein shown, my mode of presenting the web differing radically from his, in that in his mode the feed is simultaneous with the printing, while in my mode the feed takes place while the impression is thrown off.

What I claim as my invention is—

1. In combination with a stationary bed and an impression-cylinder traveling over it, guides for the web, one at each side of the impression-cylinder, and a feeding device which feeds the proper length of web while the impression is thrown off, all substantially as described.

2. In combination, two stationary beds, two traveling impression-cylinders, and a feeding mechanism, substantially as described, combined together and with suitable guides, substantially as described, and operating to print both sides of a web, as set forth. 105

3. In combination, two stationary beds, two traversing impression-cylinders, and a third printing mechanism, substantially as described, with an intermittent web-feeding mechanism, substantially as described, common to all three printing mechanisms, the first stationary form and its cylinder printing one side of a given length of web, the second printing the other side of that length of web, and the third printing mechanism printing on 115 the same length of web already printed by the other two, all as set forth.

4. In combination, two beds, two impression-cylinders, a reciprocating carriage, and two sets of inking apparatus, both cylinders 120 and both sets of inking apparatus being carried by the carriage, all substantially as described.

5. In combination, the two vertical stationary beds, their traversing impression-cylinders, and the carriage reciprocating vertically between the beds, arranged together so that the type-beds face each other and the carriage reciprocates vertically between them, as set forth. 125

6. In combination, two beds, two impression-cylinders, their carriage, and mechanism arranged and operating, substantially as described, to throw the cylinders each toward

the other at the end of the impression-stroke of the carriage, and to throw each cylinder away from the other at the end of the back-stroke of the carriage.

5. 7. The web-perfected press above described, consisting of the two stationary beds, the two traversing impression-cylinders, the two sets of inking apparatus, the web-guiding mech-

anism, substantially as described, and the intermittently-operating web-feeding mechanism, substantially as described, all operating together substantially as described.

WELLINGTON P. KIDDER.
